ABSTRACT

A contact-less limit switch for path-responsive release of switching procedures, which comprises a housing, a magnet producing a magnetic field and disposed in the housing. At least one field plate has electric current flowing therethrough, and is disposed within the range of the magnetic field. The resistance of the at least one field plate is variable by the magnetic field, and a member is provided which is operable from the outside for varying within selected limits the density or position of the magnetic field with respect to the field plate.

NON-CONTACTING LIMIT SWITCH

The present invention relates to a contact-less limit switch, in general, and to such a limit switch for a path-responsive release of switching purposes, in particular, whereby for production of electronic control pulses one or a plurality of current-fed field plates, as well as one or a plurality of magnets, relatively movable towards each other, are arranged.

It is known that such contact-less switches, compared with such switches having mechanical contacts, have particularly advantageous characteristics, essentially chatter-free contact performance, long life, constant-remaining transfer resistance, indifference against humidity and vibration, a high number of switching actuations and low operating force.

These characteristics are particularly important in limit switches, whereby still the following additional conditions are set: Reproduceability of the switching point, high switching exactness, switching speed independently from the operation of the switching-push rod.

It is, therefore, one object of the present invention to provide a contact-less limit switch, which has the characteristics of the known contact-less switches and beyond that also which fulfill the last mentioned conditions.

It is another object of the present invention, to provide a contact-less limit switch, wherein the field plate is disposed within the range of a magnet field, the density and/or position to the field plate is variable by an element movable from the outside and by an operation-push rod in selectable limits, respectively.

With this principle it is possible, to fulfill the mentioned requirements, whereby depending upon the prevailing special structural and functional conditions, different embodiments of the contact-less limit switch according to the present invention are provided.

With these and other objects in view which will become apparent in the following detailed description, the present invention, which is disclosed by example only, will be clearly understood in connection with the accompanying drawings, in which:

FIG. 1 is an axial section of the contact-less limit switch, designed in accordance with the present invention;

FIG. 2 is an axial section of the contact-less limit switch including two magnets;

FIG. 3 is an axial section of the contact-less limit switch including two magnets, disclosing another embodiment;

FIG. 4 is an axial section of the contact-less limit switch, showing another embodiment of the present invention;

FIG. 5 is an axial section of still another embodiment of the present invention; and

FIG. 6 is a section of yet another embodiment of the present invention.

Referring now to the drawings, in particular to FIG. 1, a contact-less limit switch is disclosed in which in a housing 1, made preferably of synthetic material, a permanent magnet 5 having pole-shoes 6 and a field plate 3 are rigidly secured. An operating push rod 2 is equipped with a short circuit metal sheet 7, which is movable against the effect of a spring 8 in the direction towards the pole-shoes 6.

In the shown resting position of the switch, the field plate 3 is passed by magnetic lines having a predetermined density, whereby a certain resistance value sets itself in the field plate 3. In order to produce a switching the short circuit metal sheet 7 is moved in the direction to the pole shoes 6 by means of the push rod 2. By such arrangement the magnet field is displaced in the circuit metal sheet 7, whereby a maximum is obtained upon engagement between the pole shoes 6 and the short circuit metal sheet 7. In this position the field plate 3 has the lowest resistance.

The resistance variation can be used in known manner by suitable electronic means, which are disposed in a chamber 4, for the production of a switching pulse. In this case the switching point can be set reproduceable, so that a high switching exactness is obtained.

Referring again to the drawing, and in particular FIG. 2, another embodiment of a contact-less limit switch is disclosed in which an operating push rod 2, guided displaceably in the housing 1 carries a magnet 10 having pole shoes 11. A priming magnet 12 is rigidly secured in the housing 1 opposite the pole shoes 11, the pole shoes of the priming magnet 12 being formed as lock-in metal sheets 13, between which the field plate 3 is inserted.

Upon moving the operating the push rod 2, magnet 10 is moved in the direction of the priming magnet 12. The lock-in metal sheets 13 of the latter collect the magnetic field lines originating from the pole shoes 11 and guide the magnetic field lines through the field plate 3, whereby the resistance of the latter is increased. Since the equally named poles of the magnets 10 and 12 are disposed opposite each other, the return setting force is obtained from the field lines, so that a spring is superfluous.

In this embodiment the electric function can be reversed by pole reversal of one of the two magnets. In this case upon approaching each other, the effective fields of the two magnets compensate each other and the resistance in the field plate becomes smaller.

The switching exactness can be increased here by the insertion of two or more magnet systems with field plates in connection with an electronic comparison socket.

Referring now again to the drawing, and in particularly to FIG. 3, still another not engaging and contact-less limit switch is disclosed therein. A priming magnet 15 with pole shoes 16 and a field plate 3 are rigidly secured in the housing 1. Here also the pole shoes carry lock-in metal sheets 17, which are disposed at the end-sided outer wall of the housing 1.

In this embodiment the resistance variation in the field plate 3 is brought about such, that a magnet 18 passes by outside of the housing 1 in direction of the arrow P. By the lock-in metal sheets 17, the magnetic field increases its density within the range of the field plate 3 and thereby increases its resistance. Since no mechanical wear is here possible, this limit switch has a practically unlimited life term.

If in one of the magnets 15 and 18, respectively, the exciting is reversed, a reverse electric effect is obtained, as described in connection with FIG. 2. In this case the magnet 18 is moved in direction of the arrow P', during switching.

In the present embodiment, also a short circuit metal sheet could be used instead of the magnet 18, whereby then the function of the arrangement as disclosed in FIG. 1 would be obtained.

Referring now again to the drawing, and in particular to FIG. 4, a contact-less limit switch operating as a quick break switch is disclosed. A magnet 20 having a pole shoe 21 is thereby rigidly secured in the housing 1. A field plate carrier 22 with a field plate 3 is disposed opposite the pole shoe 21 and in addition an abutment 23 for an anchor formed as a see-saw 24 is provided. The latter is mounted on an edge 25 of the pole shoe 21 and has an abutment 26.

The push rod 2 operating the see-saw 24 is guided in a guide bushing 27 and is effective by means of an after slide spring 28 on the pressure pin 29, which supports itself on a shorter arm constituting a control lever on the see-saw 24.

In the shown position, the see-saw 24 is secured by the magnet 20 on the abutment 23. If now for release of a switch pulse the operating pushing rod 2 is moved in the direction towards the see-saw 24, at first the spring 28 is tensioned in particular as long until the spring force overcomes the securing force of the magnet 20, whereupon the see-saw wrenches or tears itself off the abutment 23 momentarily and changes its position relative to the field plate.

Since the see-saw 24 has a flow from the magnetic field, by its movement a sudden resistance variation is created in the field plate 3, which can be used very advantageously for controlling of electronic circuits.

A particular advantage of this embodiment resides in the fact, that in case of creeping operation of the push rod, a safe switching performance is assured, since the switching point is

exactly kept. Furthermore, by corresponding measurements any selected transmission ratios between the movement of the push rod and of the see-saw can be obtained.

In the chamber 4 the electronic means 30 having a guide plate 31 are arranged, which means are connected directly to the field plate. 5

Referring now again to the drawing, and in particular to FIG. 5, a contact-less limit switch is disclosed in which a magnet 32 having pole shoes 33 connected with the push rod 2 is displaceably guided in the housing 1, and is retained in resting position by the spring 34. The pole shoes 33 are joined towards each other except a small air split 35, whereby at this point a high concentration of the magnetic flux is brought about. 10

Upon operation of the push rod 2 and upon movement of the magnet 32 against the field plate 3, respectively, the latter is dispensed in the air split 35, whereby the resistance in the field plate varies. By the high magnetic field density in the air split 35, the resistance difference obtainable in the field plate is likewise great, which has a favorable influence on the release of the switch pulse and the switching exactness. 15

Referring still again to the drawing, and in particular to FIG. 6, a contact-less limit switch is disclosed, the switching point of which is adjustable. For this purpose one or a plurality of magnets 37, 38 are disposed on a rotary disc 39, which is mounted in the housing 1, and is adjustable from the outside. The pole shoes of the magnets 37, 38 are equipped again with an air split 40. The field plate 3 sits on a shaft 41 concentrically arranged to the rotary disc 39, which shaft 41 can be rotated for instance by a toothed segment 42 via the angular lever 43 and a pressure pin 44 by means of the push rod 2, whereby the switching movement of the push rod 2 takes place against the effect of a return setting spring 45, which tensions during the return stroke into the shown resting position, a further return spring 46. The latter can be used simultaneously as connecting conduct between the field plate and the electronic means. 20

During insertion of the push rod 2, the angular lever 43 follows the movement of the push rod 2, since it is moved by the pretensioned spring 46, over the parts 41 and 42. The field plate is thereby suspended in the air strip 40 of the magnet 38 and varies its resistance value, whereby the switching is released. The switch timing point can be set by rotation of the disc 39, which feature can be of advantage in a limit switch. 25

The design of the switch in accordance with FIG. 6 makes possible the use as a limit value indicator between plus- and minus-tolerances, whereby then depending upon the deflection of the key, the field plate is suspended in one magnet 37 or the other magnet 38 and produces pulses, which are usable, for instance, for sorting out during the surface examination of the work pieces. 30

While I have disclosed several embodiments of the present invention, it is to be understood that these embodiments are given by example only and not in a limiting sense. 35

I claim:

1. A contact-less limit switch for path-responsive release of switching procedures, comprising
a housing,
a movable permanent magnet producing a magnetic field and disposed in said housing, 60
at least one field plate having electric current flowing therethrough,
said field plate being disposed within the range of said magnetic field,
the resistance of said at least one field plate being variable by said magnetic field,
a member operable from the outside for varying within selected limits the density or position of said magnetic field with respect to said field plate and
fixed position permanent magnet pole shoes disposed in said housing and carrying a narrow air gap, 65
a fixed position permanent magnet disposed in said fixed position permanent magnet pole shoes,
said fixed plate disposed in said air gap, and

movable pole shoes carried on the ends of said movable permanent magnet, and which project in a direction toward said fixed position permanent magnet pole shoes of said fixed position magnet, and are dimensioned such that with a shifting of said movable permanent magnet in the direction of said field plate, front surfaces of said movable pole shoes contact corresponding counter surfaces of said fixed position permanent magnet pole shoes, constituting abutment surfaces operatively limiting the movement of said movable permanent magnet. 10

2. The contact-less limit switch, as set forth in claim 1, wherein

said front surfaces of said movable pole-shoes of said movable permanent magnet are parallel to the part of an opposite front surface of said fixed position permanent magnet pole-shoes of said fixed position permanent magnet. 15

3. The contact-less limit switch, as set forth in claim 1, wherein

both of said permanent magnets arranged inside of said housing are magnetized with equal poles cross to the direction of their displacement relative to each other. 20

4. A contact-less limit switch for path-responsive release of switching procedures, comprising

a housing,
a magnet producing a magnetic field and disposed in said housing,
at least one field plate having electric current flowing therethrough,
said field plate being disposed within the range of said magnetic field,
the resistance of said at least one field plate being variable by said magnetic field,
a member operable from the outside for varying within selected limits the density or position of said magnetic field with respect to said field plate,
said magnet has a pole-shoe,
said field plate is rigidly inserted in said pole-shoe, and
a short-circuit metal sheet is spring-biased and movable in the direction towards said pole-shoe and varying the density of said magnetic field. 30

5. A contact-less limit switch for path-responsive release of switching procedures, comprising

a housing,
a magnet producing a magnetic field and disposed in said housing,
at least one field plate having electric current flowing therethrough,
said field plate being disposed within the range of said magnetic field,
the resistance of said at least one field plate being variable by said magnetic field,
a member operable from the outside for varying within selected limits the density or position of said magnetic field with respect to said field plate, 40

said member operable from the outside comprises a push rod,
a spring operatively connected to said push rod,

said magnet has pole-shoes and is displaceably guided by said push rod against the force of said spring, and
said pole-shoes lead towards each other defining therebetween a small air split, into which said field plate penetrates upon operation of said push rod. 45

6. A contact-less limit switch for path responsive release of switching procedures, comprising

a housing,
a magnet producing a magnetic field and disposed in said housing,
at least one field plate having electric current flowing therethrough,
said field plate being disposed within the range of said magnetic field,
the resistance of said at least one field plate being variable by said magnetic field, 50

a member operable from the outside for varying within selected limits the density or position of said magnetic field with respect to said field plate,
said member operable from the outside comprises a push rod,
a rotary disc settable from the outside,
said magnet having an air split is secured to said rotary disc,

said field plate is disposed on an axis concentric to said rotary disc and can penetrate said air split by the movement of said push rod for release of a switching pulse, and speed reducing means are provided for transmission of the switch movement of said push rod to said field plate.
